MACHINE FOR SEPARATING PAPER SHEETS
FROM INTERLEAVED CARBON SHEETS

Kenneth K. Keffer, New Holland, Pa.

Application September 27, 1952, Serial No. 311,829

18 Claims. (Cl. 271—2.1)

1

My invention relates broadly to machines for separating paper sheets from interleaved carbon sheets and more particularly to an improved method and apparatus for rapidly separating paper sheets from interleaved carbon sheets with minimum handling of the sheets.

One of the objects of my invention is to provide an improved method for separating paper sheets from interleaved carbon sheets by which the paper and the carbon sheets are removed in opposite directions from an interleaved sheet pack.

Still another object of my invention is to provide an improved method for separating paper sheets from interleaved carbon sheets which consists in vertically suspending the interleaved sheets and alternately withdrawing the paper sheets and the carbon sheets from the suspended pack of sheets by longitudinal movement in opposite directions.

Another object of my invention is to provide an improved machine for separating paper sheets from interleaved carbon sheets having means for alternately withdrawing the paper and carbon sheets in opposite longitudinal directions from interleaved forms by operations which require minimum handling of the sheets.

Still another object of my invention is to provide a construction of paper separating machine operating upon normally folded forms and employing positive drive means for withdrawing the sheets from the interleaved forms within a minimum of physical overall area of space and with a very substantial saving in labor.

Still another object of my invention is to provide an arrangement of adjustable rack for suspending interleaved paper and carbon sheet forms in a position by which alternate paper and carbon sheets may be withdrawn from the suspended forms in opposite directions at relatively high speed and with minimum physical handling.

A still further object of my invention is to provide an improved machine for separating paper from interleaved carbon sheets in multiple folded office forms wherein the machine is readily adjustable to accommodate a wide variety of sizes and number of interleaved sheets requiring separation.

Other and further objects of my invention reside in the improved method of interleaved sheet separation and machine for effecting such separation as set forth more fully in the specification hereinafter following by reference to the accompanying drawings, in which:

Figure 1 is a perspective view of the sheet sep-

arating machine of my invention, showing the mechanism for removing one of the sheets from the interleaved carbon and paper multiple folding forms; Fig. 2 is a vertical longitudinal view taken through the machine shown in Fig. 1; Fig. 3 is an enlarged fragmentary view of one end of the separating machine illustrating the manner in which the carbon sheet is removed from the interleaved carbon and paper sheets; Fig. 4 is a horizontal sectional view taken substantially on line 4—4 of Fig. 2; Fig. 5 is a top plan view of the separating machine; Fig. 6 is an enlarged vertical sectional view taken transversely of the adjustable suspension bars and showing the manner of suspending the multiple interleaved carbon and paper sheet forms; Fig. 7 is an enlarged elevational view showing the manner of driving the coacting rolls employed for withdrawing the paper or carbon sheets from the interleaved multiple forms suspended on the adjustable rack of the separating machine; Fig. 8 is a transverse sectional view taken through one set of the coacting rollers, and showing the manner of mounting the rollers for mutual adjustment with respect to each other and the manual means for initially revolving the rollers while feeding a paper or carbon sheet therebetween, the rollers being partially broken away to illustrate the resilient surfacing thereof; Fig. 9 is a view similar to the view illustrated in Fig. 8, but showing the coacting rollers separated for the introduction of a sheet therebetween preparatory to the withdrawal thereof from the folded suspended interleaved pack; Fig. 10 is a cross sectional view taken substantially on line 10—10 of Fig. 8; Fig. 11 is a cross sectional view taken substantially on line 11—11 of Fig. 9; Fig. 12 is a cross sectional view taken substantially on line 12—12 of Fig. 9 and illustrating the coacting rollers separated for the introduction and feeding of a sheet therebetween; Fig. 13 is a detail view showing one of the roller suspension links mounted for eccentric adjustment; Fig. 14 is a vertical sectional view taken on line 14—14 of Fig. 13; and Fig. 15 is a detail view illustrating the manner of mounting the transverse bars constituting the rack of the separating machine for suspending the multiple interleaved carbon and paper sheet office forms preparatory to separation of the forms using the method and machine of my invention.

Heretofore in the art machines proposed for separating carbon and paper sheets in office tabulating, accounting, and statistical data forms, have required very substantial labor and

time in the operation of such machines and have necessitated very substantial floor space for the installation of the equipment. Such prior apparatus has depended upon gravity forces in its operation and has been subject to the disadvantages of adherence of the paper sheets due to the generation of static electricity incident to the movement of the paper sheets which has often resulted in shutdown of the equipment. Such prior machines have been of an inconvenient height from the floor resulting in inconvenience to office workers and in separating the carbon sheets have necessitated the withdrawal of the carbon sheets by hand from the waste position which at best results in an untidy condition for both the workers and the office in which the machine is operated.

Moreover, such prior machines must have been built to accommodate office forms of a prescribed size and have not been readily adaptable to office forms of a different size. Such prior machines have performed the separating function by movement of the carbon and the paper sheets in the same direction, requiring a halting of operation as soon as a congested condition of waste carbon beneath the machine is reached.

In the method and apparatus of my invention I eliminate all of the difficulties hereinbefore experienced and provide a machine of convenient height and size for office installation which is readily portable for operation in any desired location in the office.

The machine of my invention includes an adjustable rack adapted to readily receive a folded pack of interleaved carbon and paper sheets of a wide variety of sizes and number of interleaved forms. The rack is readily adjustable to enable the forms to be spread apart and suspended thereon in a position in which the paper and carbon sheets may be alternately introduced into feed roll assemblies at opposite ends of the machine and driving forces applied to the feed roller assemblies for positively withdrawing the paper sheets in one direction and the carbon sheets in the opposite direction. The operation is rapidly performed with minimum of handling. The paper sheets with the tabular data thereon are delivered at one end of the machine for fan folding into a compact space for future use and/or filing, while the carbon sheets are delivered to the other end of the machine for reclaiming or for deposit into a refuse receptacle. The entire operation is performed so rapidly that labor up to 800 percent and time up to 1700 percent has been saved by the method and machine of my invention as compared to an operation of a manual character.

Referring to the drawings in more detail, reference character 1 indicates the frame of the paper and carbon sheet separating machine having vertically disposed standards 1a, 1b, 1c and 1d terminating at their lower ends in supporting rollers or casters 2a, 2b, 2c and 2d. The standards 1a, 1b, 1c and 1d each have sleeves designated at 3a, 3b, 3c and 3d adjacent their lower ends immediately above the rollers or casters for providing connecting means for the horizontally extending frame 6. The standards 1a, 1b, 1c and 1d carry adjustable sleeves 5a, 5b, 5c and 5d thereon which may be selectively set in position on the standards and provide connecting means for the horizontally extending frame 6. The horizontally extending frame 6 is vertically adjustable on the standards 1a, 1b, 1c and 1d by shifting the sleeves 5a, 5b, 5c and 5d thereon to the

position at which the fan-fold sheets suspended on the machine may be supported by means of horizontally extending bars 64 and 65 which depend from the frame 6 by means of brackets 64a and 64b and 65a and 65b. The bars 64 and 65 serve to support the lower loops of the fan-fold sheets at the looped ends thereof relieving the weight of the sheets and facilitating the separating operation described more fully hereinafter. The bars 64 and 65 establish substantially tangential contact with the depending looped ends of the fan-folded multiple interleaved sheets. The standard 1a supports a bracket 7 for the driving motor 8 and also forms a mounting means for control switch 9 which controls the power supply to motor 8 from the lower leads 10.

The standards 1a, 1b, 1c and 1d also provide mounting means for the adjustable sleeves 11a, 11b, 11c and 11d which may be selectively located in a predetermined vertical position on the standards to provide supports for the horizontally extending frame consisting of connecting members 12a, 12b, 12c and 12d. The connecting members 12a and 12b extend longitudinally of the frame of the machine and provide mounting means for the spacially transverse bars 14 with intermediate limiting separator sleeves 15 located therebetween. The horizontally extending frame 12, 12b, 12c and 12d is vertically adjustable and the transverse bars 14 are spacially adjustable to accommodate the machine for operation on a wide variety of multiple paper and carbon interleaved fan-fold packs as they are completed on a tabulating or a statistical machine, the vertical adjustment providing for packs of different lengths as the sheets are suspended downwardly in a vertical position on bars 14 and the adjustable spacing between bars 14 serving to accommodate fan-fold packs of different numbers of interleaved sheets. The length of transverse bars 14 between the longitudinally extending frame members 12a and 12b is selected so that they are of a suitable dimension to accommodate such length of sheets constituting the fan-fold sections as the machine may be required to accommodate over a variety of different kinds of office machines.

The standards 1a, 1b, 1c and 1d serve as supporting means for coacting rollers which serve to withdraw the paper and carbon sheets in opposite directions at the top of the machine. Standards 1d and 1c respectively support frames 16 and 17 at the top thereof. These frames are each divided into upper and lower sections, that is, 16a and 16b; and 17a and 17b, respectively. The lower sections 16b and 17b provide mounting means for the two pairs of spaced coacting drawing rollers 20a and 20b and 21a and 21b for drawing paper through one end of the machine from the interleaved fan-fold sheets suspended on the rack constituted by transverse bars 14.

At the other end of the machine, frames 18 and 19 are mounted on the upper ends of standards 1a and 1b and serve as mounting means for the pairs of coacting rollers 22a and 22b and 23a and 23b which operate to draw the carbon sheets from the interleaved sheets on the rack constituted by bars 14 through the opposite end of the machine.

The pairs of coacting rollers carried by the frames at the top of the machine are driven through intermediate gears 24 and 25, respectively. The construction of each of the sheet withdrawing units at opposite ends of the machine is symmetrical and a description of one of

the units as set forth in Figs. 7-14 will be sufficient for purposes of explaining the details of both units.

Referring to Figs. 7-14 it will be observed that the upper rollers 20a and 21a of each of the coacting sets of rollers are resiliently supported in bearings which float with respect to the bearings in which the lower coating rollers 20b and 21b are mounted. This is accomplished by providing vertically disposed slots 16d and 16e in the lower section 16b of frame 16 and aligned slots 17d and 17e in lower section 17b of frame 17 within which blocks 26 and 27, and 28 and 29, respectively, are resiliently suspended by means of coil springs shown at 30. The coil springs 30 are located between recesses countersunk beneath the upper sections 16a and 17a of the frames 16 and 17 and extending into recesses formed in the blocks 26, 27, 28 and 29. The blocks 26, 27, 28 and 29 each have a pin member shown at 26a, 28a and 29a depending from the bottom thereof and variably projecting into bores at 16f and 17f in the lower sections 16b and 17b, for example, to serve as guides for the vertical movement of the floating roller of each of the coating sets of rollers. Thus the top roller of each of the coating sets of rollers moves toward and away from the bottom coating roller while being maintained in vertical alignment therewith. Each of the rollers such as 20a and 20b for example are provided with resilient coatings 20a' and 20b'. The upper rollers of each of the sets of coating rollers are journaled as shown for example at 20a'' in the lower sections 16b and 17b of frames 16 and 17. In Fig. 11 I have shown the journals for the lower rollers at 20b'' and 21b''. It will be understood that the manner of assembling the other units is identical.

The shafts for the lower rollers of each of the coating sets of rollers are each provided with gears as shown for example at 20c and 21c which, in this particular arrangement, are intermeshed by means of gear 24. The arrangement at the opposite end of the machine is the same as shown more clearly in Fig. 5 where intermediate gear 25 meshes with the gears which drive the lower rollers of each of the coating sets of rollers.

The bearings for the upper roller of each of the coating sets of rollers as illustrated in Figs. 7-12, for example, are vertically adjustable. This is accomplished by suspending the shaft which carries the upper roller of each of the sets of coating rollers on links 31, 32, 33 and 34, shown in more detail in Figs. 13 and 14. Each link is eccentrically mounted by an arrangement of angularly shiftable shafts shown at 35, 36, 37 and 38. The shafts are journaled in the upper sections 16a, 17a, 18a and 19a of the frames 16, 17, 18 and 19, respectively. Each shaft carries an eccentric sleeve-like cam, represented at 35' and 36', and 35'' and 36'', adjacent opposite ends thereof operating within apertures in the upper portions of the suspension links so that as the shaft, shown at 36 for example, is revolved the links and the rollers associated therewith are effectively raised or lowered in a vertical direction. The rotation of shafts 35, 36, 37 and 38 is accomplished by means of manually operated levers shown at 40, 40', 41, 41', 42, 42' and 43, 43' for respectively controlling the adjustment of each end of the upper roller of the coating sets of rollers for setting the spacial relation of the nip of the rollers for most effectively operating upon the paper and carbon sheets.

The assembly of the sets of rollers within the mounting frames is readily accessible for repair, adjustment and replacement of parts as the upper section of each mounting frame is readily removable and replaceable with respect to the lower section by means of the screw 17c for example in the unit shown in Figs. 7-12.

The feeding of the carbon or paper sheets into the nip of the coating rollers is initially accomplished by means of a manually operated hand wheel 44 or 45 which is mounted on the shaft of the lower roller represented at 20b and 22b and serves to revolve the gear 20c and 22c imparting movement to all of the other coating rollers for a sufficient time period to enable the paper or carbon sheet to be started through the machine. If the paper or carbon sheet has been started through the coating rollers, switch 9 is operated, operating motor 8 which drives belt 46 operating over pulley 47 carried by shaft 23b'' which revolves lower roller 23b and gear 23c associated therewith. Rotative movement is transmitted through an intermediate gear 25 to gear 22c on shaft 22b'' which carries roller 22b. Shaft 22b'' carries bevel gear 48 which meshes with bevel gear 49, driving shaft 50. Shaft 50 is journaled longitudinally between frames 18 and 16 and carries bevel gear 51 at the end thereof. Bevel gear 51 meshes with bevel gear 52 on shaft 20b'', thereby imparting motion to roller 20b. Gear 20c is thus driven which meshes with intermediate gear 24, driving gear 21c, thus activating all of the sets of coating rollers. As each paper sheet is fed to the nip of the roller 20a, 20b and manually adjusted to feed therethrough, motor 8 is started resulting in the withdrawal of the paper sheet 53, as shown in Fig. 2, from the interleaved carbon and paper sheets shown at 54 suspended in fan fold arrangement on the transverse bars 14. Similarly the carbon sheet represented at 55 in Fig. 3 is manually fed between the nip of rollers 22a and 22b to start the carbon paper therethrough and between rollers 23a and 23b and thereafter the motor started for drawing the carbon sheet through the machine in the opposite direction.

I provide a guide at each end of the machine for directing the paper into the paper feed rolls as represented at 56 in Fig. 2, where the guide is supported on opposite ends on frames 16 and 17 and braced in an intermediate position by means of bracket 57. The paper sheet 53 glides over the rounded surface of guide 56 entering the nip of rollers 20a and 20b. As the paper passes through coating rollers 21a and 21b it is guided over a similar guide surface, which I have represented at 58, supported by intermediate bracket 59. Similarly, the carbon paper 55 is guided, as represented in Figs. 2 and 3, over a guide surface represented at 60 supported between frames 18 and 19 and braced in an intermediate position by bracket 61. The carbon paper as it passes through the coating sets of rollers 22a, 22b, 23a and 23b is guided to a deposit receptacle over guide 62 mounted between frames 18 and 19 and braced in an intermediate position by bracket 53.

The machine of my invention thus controls the withdrawal of paper sheets as represented in Fig. 2 in a longitudinal direction toward the right, while the carbon sheets are withdrawn in a longitudinal direction toward the left as indicated in Fig. 3.

It will be understood that in starting the machine the paper sheets are fed through the coacting sets of rollers 21a and 21b, and 20a and

20b, and thereafter the positive drive of the motor takes over and the paper sheet is zipped rapidly through the machine and out of the fan fold form to a position where the paper sheets may be refolded and filed away for future reference. On the other hand, the carbon sheets after being initially fed through rollers 22a and 22b and 23a and 23b are then positively withdrawn from the fan fold suspension by operation of the motor 8.

The transverse bars 14 do not fill the entire length of the longitudinally extending members 12a and 12b and adequate space is allowed for special adjustment of bars 14 along members 12a and 12b as shown for example in Figs. 1-5 and 15. When the machine is used for separating fan fold forms of a predetermined size and number of sheets the sleeves 15 may be set in a predetermined position by means of set screws shown at 15a to accommodate the machine for the predetermined size of interleaved fan-fold sheets.

In lieu of the complete withdrawal of one sheet in advance of the withdrawal of the adjacent sheet, I may expedite the separation process by starting the withdrawal of one sheet in one direction and then as soon as the free end of the immediately adjacent sheet is accessible the withdrawal of the said adjacent sheet can be started thereby accelerating the separation process.

Moreover, I may arrange the machine of my invention so that single pairs of rolls may be employed for withdrawing the sheets in lieu of the compound arrangement of rolls utilized for withdrawing the sheets. In certain instances, I may withdraw both paper and carbon sheets in sequence, through the same end of the machine, by first withdrawing a sheet of one characteristic and next withdrawing the sheet of the other characteristic.

While I have described my invention in certain preferred embodiments, I realize that modifications and improvements may be made and I desire that it be understood that no limitations upon my invention are intended other than may be imposed by the scope of the appended claims.

What I claim as new and desire to secure by Letters Patent of the United States is as follows:

1. A machine for separating paper sheets from interleaved carbon sheets comprising a rack for suspending fan folded multiple interleaved paper and carbon sheets with the free ends of said sheets accessible adjacent one end of said machine and positively driven sheet withdrawing means disposed at each end of the machine, one of said means being operative to grip and withdraw paper sheets from said interleaved sheets in one direction and the other of said means being operative to grip and withdraw the carbon sheets in the opposite direction.

2. A machine for separating paper sheets from interleaved carbon sheets comprising a frame supporting roller feed means at each end thereof, a plurality of adjustably spaced lateral bars mounted on said frame intermediate said roller feed means said bars being spaced to receive and support fan folded multiple interleaved paper and carbon sheets with the free ends of the sheets terminating at one end of said frame in a position from which the individual sheets may be separately introduced into said roller feed means and said paper sheets removed from said fan folded sheets in one direction and said car-

bon sheets removed from said fan folded sheets in the opposite direction.

3. A machine for separating paper sheets from interleaved carbon sheets as set forth in claim 2 in which said roller feed means are each constituted by two pairs of coacting rollers geared to each other, both of said pairs of coacting rollers at one end of the machine acting to move the paper sheets through one end of said machine and both of the pairs of coacting rollers at the other end of the machine operating to move the carbon sheets through the last mentioned end of the machine.

4. A machine for separating paper sheets from interleaved carbon sheets as set forth in claim 2 in which each roller feed means includes a manually operated controller for revolving said roller feed means for initially feeding said sheets between the nips of said roller feed means.

5. A machine for separating paper sheets from interleaved carbon sheets as set forth in claim 1 in which a guide member is interposed between one end of said rack and one of said sheet withdrawing means for directing the said sheet into the sheet withdrawing means.

6. A machine for separating paper sheets from interleaved carbon sheets as set forth in claim 1 in which a guide member is located between each end of said rack and each of the sheet withdrawing means, one of said guide members operating to direct and guide paper sheets and the other of said guide members operating to direct and guide carbon sheets.

7. A machine for separating paper sheets from interleaved carbon sheets as set forth in claim 1 in which said positively driven sheet withdrawing means are operated by the same motor device and gear means driven by said motor device for operating one of said sheet withdrawing means through the other of the sheet withdrawing means.

8. A machine for separating paper sheets from interleaved carbon sheets as set forth in claim 1 in which said rack consists of a plurality of transversely disposed spaced bars supported at opposite ends, said bars being adjustable in spacial relation to accommodate fan folded multiple interleaved paper and carbon sheets of differing dimensions and plies.

9. A machine for separating paper sheets from interleaved carbon sheets as set forth in claim 2 in which said roller feed means are each constituted by two pairs of coacting rollers wherein one roller of each coacting pair is vertically adjustable toward and away from the other coacting roller for facilitating the gripping of said sheets between the nips of the rollers.

10. A machine for separating paper sheets from interleaved carbon sheets comprising a vertically extending frame, a horizontally disposed frame adjustable to selected positions on said vertically extending frame, said horizontally disposed frame including a pair of longitudinally extending spaced members, a multiplicity of transversely disposed bars supported at opposite ends by said longitudinally extending spaced members, limiting separators between said bars for limiting the approach of one bar with respect to an adjacent bar, said bars serving to suspend fan fold multiple interleaved paper and carbon sheets with the free ends of said sheets accessible adjacent one end of said frame, paper sheet removing means carried by one end of said frame and carbon sheet removing means carried by the other end of said frame.

11. A machine for separating paper sheets from

interleaved carbon sheets comprising a frame, a motor carried by said frame, a set of coacting rollers journaled adjacent one end of said frame, a separate set of coacting rollers journaled adjacent the other end of said frame, manual means for each set of said rollers for independently revolving each set of said rollers, means operated by said motor for driving both of said sets of coacting rollers, a rack carried by said frame intermediate said sets of coacting rollers for suspending fan fold sheets of interleaved carbon and paper sheets with the free ends of said sheets terminating in a position accessible to each of said sets of coacting rollers, whereby said paper and carbon sheets may be alternatively introduced through the sets of coacting rollers and withdrawn from said interleaved fan folds, the paper sheets moving in one direction and the carbon sheets moving in the opposite direction.

12. A machine for separating paper sheets from interleaved carbon sheets as set forth in claim 11 including guide means associated with each of said coacting sets of rollers and interposed between said rack and the respective sets of coacting rollers whereby the paper and carbon sheets are independently directed into the nips of the sets of coacting rollers.

13. A machine for separating paper sheets from interleaved carbon sheets as set forth in claim 11 in which said sets of coacting rollers include manual means for revolving said rollers independently of the driving forces imparted thereto from said motor.

14. A machine for separating paper sheets from interleaved carbon sheets as set forth in claim 11 in which said sets of coacting rollers each includes a lower roller and an upper roller and adjustable eccentric means for controlling the position of the upper roller with respect to the lower roller while maintaining the vertical alignment of said upper roller with respect to said lower roller.

15. A machine for separating paper sheets from interleaved carbon sheets as set forth in claim 11 in which said sets of coacting rollers each includes a lower roller and an upper roller and manually controlled means for adjusting the position of the upper roller with respect to the lower roller while maintaining the vertical alignment of said upper roller with respect to said lower roller.

16. The method of separating paper sheets from interleaved carbon sheets in a fan folded multiple interleaved paper and carbon sheet pack which

consists in spreading the fan folded multiple interleaved sheets in a horizontal direction, suspending the fan folded sheets vertically with the interleaved paper and carbon sheets accessible from the top thereof and withdrawing the paper sheets and carbon sheets alternately in opposite longitudinal directions from opposite ends of the fan folded pack while maintaining the fan folded sheets in suspension.

17. The method of separating paper sheets from interleaved carbon sheets in a fan folded multiple interleaved paper and carbon sheet pack which consists in spreading the fan folded multiple interleaved sheets in a longitudinal direction, suspending the fan folded sheets vertically with the interleaved paper and carbon sheets accessible from the top thereof, positively gripping the free end of the paper sheet and forcefully withdrawing the paper sheet from the interleaved suspended pack, thereafter gripping the free end of the next succeeding interleaved carbon sheet and forcefully removing the said carbon sheet in the opposite direction while maintaining the interleaved sheets in suspended position and recycling said operations until all of the interleaved paper and carbon sheets are removed from the suspended pack.

18. A machine for separating paper sheets from interleaved paper and carbon sheets comprising a rack for suspending fan folded multiple interleaved paper and carbon sheets with the loops thereof depending downwardly and means adjustably supported on said rack and establishing substantially tangential contact with the looped ends of said fan folded sheets for supporting said fan folded sheets at the depending ends thereof.
